United States Patent Office

Des. 183,414
Patented Aug. 19, 1958

183,414

INTERNAL WRENCH

Joseph F. Woerner, Houston, Tex.

Application August 31, 1956, Serial No. 42,800

Term of patent 14 years

(Cl. D54—16)

Fig. 1

Fig. 2

Fig. 4

Fig. 3

Fig. 5

Figure 1 is a side elevational view of an internal wrench showing my new design;

Figure 2 is an elevational view of the same, taken from the right hand side of the wrench as illustrated in Figure 1;

Figure 3 is a bottom plan view of the wrench as illustrated in Figure 1;

Figure 4 is a top plan view of the wrench as illustrated in Figure 2; and

Figure 5 is a view similar to that of Figure 1, showing the appearance of the wrench in use.

I claim:

The ornamental design for an internal wrench, as shown.
